DONALD J. MOSSHART, OF PHILADELPHIA, PENNSYLVANIA, ASSIGNOR TO WESTINGHOUSE ELECTRIC & MANUFACTURING COMPANY, A CORPORATION OF PENNSYLVANIA

ACTUATING MEANS FOR FUEL AGITATORS

Application filed May 22, 1925. Serial No. 32,103.

My invention relates to means for intermittently operating the control of a power cylinder for predetermined periods of time and more particularly it has reference to means for so operating the control mechanism of the fluid pressure cylinder commonly employed to operate fuel agitating means as employed on the grate surface of automatic stokers, and it has for its object to provide apparatus of the character designated which shall be simple, rugged and inexpensive in construction and which shall be extremely flexible in operation, permitting any desired control of the agitating effect within prescribed limits.

In the accompanying drawings, Fig. 1 is a side view, partially in section and partially in elevation, of an automatic stoker of the underfeed type illustrating the application of my invention thereto; and Fig. 2 is a perspective view showing my invention more in detail.

In the operation of automatic stokers, particularly of the large size underfeed type, it frequently happens that the fuel bed at the rear of the stoker is of such thickness and of such dense formation that it is difficult to pass sufficient air thereto to burn out the combustible. It has been proposed therefore to provide an agitating means at the rear of such furnaces in order to break up these dense fuel masses.

It has been found undesirable to operate such agitators continuously as combustion is interfered with, and accordingly it is desirable to operate these agitating means only for a short period at a time, permitting the fuel bed to assume a more or less quiescent state between periods of operation.

In accordance with the present invention, I employ a fuel agitator driven by a fluid pressure cylinder, such for example, as a steam cylinder, and the valve gear of said cylinder is operated as from the main ram drive through the intermediary of a pawl mechanism whereby the valve mechanism is operated for predetermined intermittent periods, the frequency of such periods being under the control of the operator.

Referring to the drawing for a more detailed understanding of my invention, I show

the main grate portion of a stoker of the underfeed multi-retort type at 10 in Fig. 1, fuel being introduced thereto through a front wall 11 as by a ram 12, all as is well-known and understood in the art.

The fuel agitator is disposed behind the main grate surface 10 and may take, for example, the form shown in U. S. application Serial No. 643,368, filed June 4, 1923, by the Westinghouse Elec. & Manufacturing Company on an invention of Otto Aram. Briefly speaking, a tilttable member 13 has a rocking member 14 overlying the front end thereof, said members preferably being perforated for the admission of air to the fuel lying thereon. The member 13 may be rocked as by an arm 15 and a link 16, such rocking also causing a rocking motion of the member 14.

The link 16 is connected to the piston 17 of a steam cylinder 18 and steam may be admitted thereto by any desired means such, for example, as a dumbbell valve 19 having an operating stem 20.

Referring more particularly to Fig. 2, the operating stem 20 carries a lug 21 disposed in proximity to a notched disc 22 mounted on a shaft 23—23, said shaft also carrying a toothed disc 24.

A bridle member 25 is pivoted on the shaft 23 and carries a main pawl 26 and a secondary pawl 27. The main pawl 26 rides upon the periphery of the disc 22 but is somewhat wider than the thickness of said disc so that this pawl overlies the lug 21 on the valve stem 20. The arrangement is such that if the pawl operating bridle be oscillated with the pawl 26 in a notch of the disc 22, it may engage with the dog 21 on each forward stroke, resulting in a reciprocation of the valve 19. If, however, on the other hand, the pawl 26 is riding on a tooth of the disc 22 between two notches, it is restrained out of contact from the dog 21 and oscillation thereof does not affect the valve 19.

The secondary pawl 27 bears on the periphery of the disc 24 so that oscillation of the bridle 25 causes said pawl to rotate said disc.

A pawl guard 28 is provided to control the

action of the pawl 27 upon the disc 24, said pawl guard being carried by a pivoted arm 29 operable as from the front of the stoker by a link 30. When the pawl guard 28 is in the position shown, the pawl 27 rests on the disc 24 at all times and forward movement of the pawl 27 produces a maximum rotation of the disc 24. When, however, the pawl guard 28 is rotated on the member 29 in a clockwise direction, it passes into the path of travel of the pawl 27, raising said pawl on the back stroke and permitting it to engage teeth only during the latter part of its forward stroke, thus effectually controlling the rate of rotation of the disc 24 and accordingly of the disc 22.

The bridle 25 is connected for oscillation to the main ram 12 as through an arm 31 and link 32.

Having thus described the structure of apparatus embodying a preferred form of my invention, the operation thereof is as follows: Assuming the stoker to be in operation and a relatively thick fuel bed to overlie the members 13 and 14, reciprocation of the ram 12 causes slow rotation of the disc 24 through the pawl 27 with attendant revolution of the disc 22. The pawl 26 rides freely for a considerable period of time because resting on top of a tooth of the disc 22 and accordingly not engaging the dog 21. After a predetermined period, however, a notch of the disc 22 comes under the pawl 26, permitting said pawl to drop and to engage the dog 21, actuating the valve mechanism, said valve mechanism being returned after action, as by a spring 33. Thus the agitators 13 and 14 will be violently rocked as, for example, two or three times and will then remain at rest for a considerable period of time before again being rocked. Thus the fuel bed is maintained in a broken-up condition and effective combustion is maintained by the passage of air through the resultant cracks.

By bringing the pawl guard 28 into play, the attendant may materially slow down the average angular velocity of the disc 24, resulting in longer periods of rest between successive periods of action of the fuel agitators.

It will be obvious that my invention may be modified in various respects without departing from the spirit thereof. Thus, for example, the pawl 26 might be caused to engage the dog 21 when riding on a tooth and to disengage therewith when riding in a notch, but I consider all such modifications to be obvious in view of the foregoing description and accordingly I desire that no limitations shall be placed upon the scope of my invention except such as are set forth herein and more particularly in the appended claims.

While I have shown my invention in but one form, it will be obvious to those skilled

in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:—

1. The combination with a progressive feed stoker including a fuel agitating grate section in the fuel supporting surface thereof, of a pressure operated piston for actuating the grate section, a valve member for controlling the piston and having a valve stem carrying a lug, a notched disc, a pawl member riding on the periphery of said disc, said pawl member being arranged to effect a driving engagement with said lug on the valve stem when riding in a notch of said disc, means for oscillating said pawl member, means for slowly rotating said disc, and means for retracting said valve member after the latter has been urged forward by the engagement of said pawl member with said dog.

2. The combination with a progressive feed stoker including a fuel feeding mechanism and a fuel agitating grate section in the fuel supporting surface thereof, of a pressure operated piston for actuating the grate section, a valve member for controlling the piston, a stem for said valve member provided with a step portion, a pawl adjacent to said step portion, an operative connection between the fuel feeding mechanism and the pawl for imparting a to-and-fro motion to said pawl, the pawl adapted to have a driving engagement with the step portion upon a movement in one direction, means for periodically altering the path of travel of the point of said pawl from a condition of engagement to a condition of non-engagement with respect to said step portion and vice-versa, and means for retracting said valve stem after movement by said pawl.

3. The combination with a progressive feed stoker including a fuel agitating grate section in the fuel supporting surface thereof, of a pressure operated piston for actuating the grate section, a valve member for controlling the piston, a valve stem for the valve member and having a lug provided thereon, a disc having notches in the periphery thereof, a main pawl of greater width than the thickness of said disc riding on the periphery of said disc in proximity to said lug, the arrangement being such that said main pawl may operatively engage said lug when riding in the bottom of a notch and be raised from an engaging position when riding between notches, a toothed disc mounted on the shaft of said notched disc, a secondary pawl riding on the periphery of the toothed disc, a bridle member mounted for oscillation on said shaft and carrying said two pawls,

means for oscillating said bridle member, a pawl guard for determining the arc of engagement of said secondary pawl with its associated disc during each oscillation, and 5 means for retracting said valve stem after actuation by said main pawl.

4. The combination with an automatic stoker including fuel-feeding means, and a fuel agitating grate section in the fuel supporting surface thereof, of a fluid pressure cylinder for actuating said grate section and having valve means for the control thereof, a valve stem for actuating said valve means and having a lateral projection thereon, a 10 toothed disc having a relatively wide main pawl riding on the periphery thereof in proximity to said lateral projection, said main pawl being adapted to engage said lateral projection when resting in a notch and being 15 raised out of engagement when riding between notches, a toothed disc mounted on the shaft of said notched disc, a secondary pawl riding on the periphery of said toothed disc, an oscillatable bridle member carrying said 20 pawls, means for oscillating said bridle member from the fuel-feeding means, a pawl guard for determining the arc of engagement of said secondary pawl with the associated disc during each oscillation, and means 25 for retracting said valve stem after it has been actuated by said pawl.

5. In a furnace, the combination with an automatic stoker including a fuel-feeding means and a fuel agitating grate section 30 forming a part of the fuel supporting surface, of means for actuating the grate section, mechanism operated in timed relation to the operation of the fuel-feeding means for controlling the operation of the 35 grate actuating means in such a manner that the grate section is agitated intermittently for predetermined periods of time, and means providing for an adjustment of the controlling mechanism so as to vary the 40 length of time between and the duration of the operating periods of the grate section.

6. In a furnace, the combination with an automatic stoker including fuel feeding means and a fuel agitating grate section 45 forming a part of the fuel supporting surface thereof, of mechanism operating in response to the operation of the fuel feeding means for intermittently operating said agitating 50 grate section for predetermined periods of time.

7. In a furnace, the combination with an automatic stoker including fuel feeding means and a fuel agitating grate section in 60 the fuel supporting surface thereof, of a fluid pressure cylinder and piston for actuating said grate section, valve means for controlling the operation of said piston, a mechanism operating in response to the 65 operation of the fuel feeding means for inter-

mittently actuating said valve means for predetermined periods of time.

8. The combination with a progressive feed stoker including a fuel agitating grate section in the fuel-supporting surface thereof, of a pressure-operated piston for actuating the grate section, a valve member for controlling the piston and having an actuating stem provided with a lateral step portion, a pawl mounted for to and fro motion and adapted, 70 when moved in one direction, to have a driving engagement with the lateral step portion, means for effecting such motion of the pawl, means providing for periodical engagement of said pawl and said step portion for predetermined periods, and means for retracting said valve stem after movement by said pawl.

9. The combination with a progressive feed stoker including a fuel agitating grate section in the fuel-supporting surface thereof, of a pressure-operated piston for actuating the grate section, a valve member for controlling the piston having a stem provided with a laterally-extending operating face, a disc having notches in the periphery thereof, a pawl riding on the periphery of said disc and in proximity to said laterally-extending face, the arrangement being such that said pawl operatively engages said face when riding in the bottom of a notch and is 80 out of engagement with the face when riding between notches, means for oscillating said pawl, means for slowly turning said disc, and means for retracting said valve stem after 85 actuation by said pawl.

In testimony whereof, I have hereunto subscribed my name this eleventh day of May, 1925.

DONALD J. MOSSHART.
